UNITED STATES PATENT OFFICE.

JOHN P. ARNDT, OF SOUTH MILWAUKEE, WISCONSIN, ASSIGNOR TO LINE MATERIAL COMPANY, OF SOUTH MILWAUKEE, WISCONSIN, A CORPORATION OF WISCONSIN.

FUSE.

Application filed March 21, 1919. Serial No. 284,059.

To all whom it may concern:

Be it known that I, JOHN P. ARNDT, a citizen of the United States, residing at South Milwaukee, in the county of Milwaukee and State of Wisconsin, have invented new and useful Improvements in Fuses, of which the following is a specification.

This invention relates to fuses.

10 One of the objects of this invention is to provide an improved method of interrupting electric circuits.

Another object of this invention is to provide an improved fuse of the enclosed type.

Another object is to provide a comparatively short fuse capable of effectively interrupting high voltage heavy current circuits.

Another object is to provide a fuse where in the circuit is positively broken when the 20 fuse-link is ruptured.

Another object is to provide a fuse which effectively prevents the reformation of any arc between its terminals.

Another object is to provide a fuse where 25 in the danger of an arc destroying the fuse cartridge is reduced.

Another object is to provide an enclosed fuse wherein the fuse-link may be readily replaced.

30 Another object is to provide an improved interchangeable fuse so that repairs need not be made where the fuse is located, or service interrupted until repairs are completed.

35 Another object is to provide a fuse wherein the fuse-link may be replaced and repairs may be made with minimum danger.

Another object is to provide an improved 40 fuse which gives an indication upon being blown.

Another object is to provide an enclosed fuse wherein the gases generated when the fuse-link is volatilized are readily allowed to escape.

45 Another object is to provide a fuse which is vented outside of its enclosing casing.

Another object is to provide a fuse of the enclosed type which is reliable in operation, easily applied, and readily manufactured.

50 Other objects will appear from the following specification and claims.

Several embodiments of the invention are illustrated in the accompanying drawings in which

55 Figure 1 is a front elevation of a fuse

in a protecting casing whose door, which is removed, forms the fuse mounting;

Fig. 2 is a partial sectional elevation thereof, the door of the casing being shown in both open and closed positions; 60

Fig. 3 is an enlarged longitudinal section of the fuse cartridge, the parts being shown in normal position;

Fig. 4 is an enlarged longitudinal section of a portion of the cartridge, showing 65 the position the parts assume when the fuse is blown;

Fig. 5 is a cross section on the line 5—5 of Fig. 4;

Fig. 6 is a front elevation of a fuse 70 mounted openly;

Fig. 7 is a side elevation thereof;

Figs. 8 and 9 are longitudinal sections of a modified construction;

Fig. 10 is a section on line 10—10 of 75 Fig. 8;

Fig. 11 is a section on the line 11—11 of Fig. 9;

Fig. 12 is a perspective of the lower switch; 80

Fig. 13 is a longitudinal sectional view of another modified construction;

Fig. 14 is an end view thereof, and

Fig. 15 is a cross section on the line 15—15 of Fig. 13. 85

Figs 1 to 5, inclusive, will first be described.

The fuse cartridge comprises, in general, a tube 1 enclosing a fuse-link and provided with terminals 2 and 3 between which the 90 link extends. The tube is rigidly secured to the back of a porcelain door 4 of an enclosing metallic housing 5. Each of the terminals 2 and 3 is provided with a switch blade 6 adapted to be pressed and held between corresponding switch clips 7 when the door is closed. Clips 7 are supported from the back of the casing on suitable insulators 8, and to these clips the line conductors are secured. The line conductors 100 enter casing 5 through insulators set in suitable pockets in the casing. When the casing door is closed the circuit is completed from one line conductor through the upper switch, terminal 2, the fuse-link, terminal 105 3 and the lower switch to the other line conductor. When the door is opened the circuit is broken.

Tube 1 is made of a suitable insulating material such as fiber. By means of a metal 110

strap 9 it is secured, near its top, to a support interconnecting the door strengthening ribs 10. The lower end of the tube is carried by a collar 11 which is also secured to the door. Projecting laterally from collar 11 are a pair of trunnions 12. These trunnions rest in open topped bearings 13 formed in projections 14 which extend inwardly from opposite sides of the casing. The door pivots upon trunnions 12 and may be readily removed by raising the trunnions from the bearings. A handle 15 is provided for the door to facilitate the opening or removal thereof. The open condition of the door is limited by a stop 16 which is carried by a pair of arms 17 extending downwardly from collar 11, engaging the bottom 18 of the casing. The engagement of the stop and bottom of the casing also prevents the door from dropping out of its bearings.

The door and casing have been described as being respectively composed of porcelain and metal. However, both may be made of metal or both of porcelain, or either or both 25 may be made of wood or other material suitable to the conditions of operation, service and location.

Referring especially to Figs. 3 and 4 the construction of the fuse cartridge will be 30 more particularly described.

The upper terminal 2 forms a cap or closure for the upper end of the outer tube 1 and is provided with an internally threaded upstanding rim 20 for the reception of a 35 clamping nut 21. It is also provided with a comparatively small opening 22 through which a fuse-link 23 extends. The end of the fuse-link, after passing through opening 22, is led through a transverse groove 24 into an annular groove 25 where it is securely clamped in position by the annular projection 26 on nut 21 when the nut is turned home. The interlocking of the groove in the terminal and the projection on the 45 clamping nut form a tight joint to prevent the escape of gas or the passage of an arc. The upper end of the inner wall of the terminal is tapered to facilitate the placing of the fuse-link. The lower terminal 3 has a screw 27 and a nut 28 for securing thereto the lower end of the fuse-link. The terminal and nut are respectively provided with an annular groove and an annular projection which interlock to prevent the escape of gas 50 through aligned openings in the tubes. The link passes through terminal 3 and the outer tube by an opening 29. Terminals 2 and 3 are secured to tube 1 by screws 30 or other suitable means.

60 Telescopically slideable within tube 1 is an inner tube 31 which is open at its upper end. The lower end of the inner tube is closed by a rubber plug and cushion 32 held in place by a pin 33. The inner tube is also composed of a suitable insulating material such

as fiber. It is provided with a small opening 34 in its side wall which is adapted to align with opening 29 in the outer tube and terminal 3 to provide for the passage of the fuse-link. These aligned openings pass 70 through the walls of the tubes and terminal 3 in a diagonal direction to facilitate the threading of the fuse-link therethrough. Near its closed end inner tube 31 is provided with a vent opening 35. This opening is positioned above the open end of outer tube 1 and closed by the side wall thereof when the inner tube is in its normal or raised position shown in Fig. 3. The two telescopically arranged tubes thus provide a substantially 75 closed pressure chamber in which the fuse-link is positioned. When the fuse is blown the inner tube is forced downward, moving the vent opening 35 below the lower edge of the outer tube allowing the gas within the 80 chamber to escape.

The inner tube is normally held in elevated position by the link passing through and engaging the walls of the aligned openings 29 and 34. In order to locate and localize the rupture of the link upon the passage of excess current therethrough, the link is provided with a restricted cross-section where it passes through the aligned openings in the tubes. This may be accomplished 90 by doubling and twisting a fuse wire upon itself for the greater portion of its length, leaving it of a single strand where it passes through the aligned openings. Thus the weakest portion of the link is at the aligned 95 openings and the rupture is localized at this point. The link may be made of fuse ribbon instead of wire. If ribbon is employed the restricted portion may be provided by making the cross section less where it passes 100 through the openings. It is not necessary to localize the rupture, but by doing so the operation is particularly satisfactory.

The operation of the cartridge is as follows: When the fuse-link is intact the telescopic tubes are in the position shown in Fig. 3. Upon the passage of excess current through the fuse-link the entire link is heated and the restricted portion thereof begins to volatilize and fuse. The heat generated 110 and the gases of volatilization produce a pressure within the chamber which forces the inner tube downward. This movement abruptly breaks the alignment of openings 29 and 34 and cuts not only whatever of the link may remain intact, but also any arc 115 which may persist to complete a circuit between the fuse terminals. When the vent opening 35 passes beyond the lower end of the outer tube the gases are allowed to escape. The movement of the inner tube is arrested by the rubber cushion 32 engaging stop 16. The impact causes no injury to the fuse because of the cushioning effect of cushion 32. The tubes are now 120 125 130

- in the position shown in Fig. 4 and since the alignment of the openings therein is broken, the walls of the tubes present a complete barrier to any reformation of the arc or 5 sparking between the terminals or the severed ends of the fuse-link. The circuit between the terminals is thus effectively broken and also, since no arc persists, the danger of destroying the cartridge is reduced. Since the 10 vent opening is now outside of the enclosing casing the gases in the chamber can escape to the open air. Thus there is no danger of these gases providing a comparatively low resistance path between the fuse terminals or 15 switch members outside of the tubes. The lower end of the inner tube also serves as an indication that the fuse has been blown, as clearly shown in Fig. 4, and the dotted line of Fig. 1.
- 20 To replace the fuse-link, nut 21 is unscrewed from the upper terminal and the upper terminal is removed from the outer tube. Nut 28 is also unscrewed and the remaining ends of the ruptured link are removed. The inner tube is next moved back 25 into the outer tube and openings 29 and 34 are aligned. The fuse-link is then inserted through the aligned openings, which may be made large enough to pass the largest portion 30 of the link, and its lower end is clamped to the lower terminal by nut 28. The upper end of the new link, which extends above the open end of the outer tube, is threaded through opening 22 and the upper terminal 35 is replaced and fastened in position. The upper end of the link is then passed through transverse groove 24 around the annular groove 25 and clamped in position by nut 21. Such replacements may be readily made 40 without danger because the opening of the casing door renders the cartridge accessible, and disconnects the cartridge terminals from the line. Another advantage of the fuse is that, because the casing doors may be easily 45 removed and made interchangeable, the door and cartridge of a blown fuse may be replaced by another door with an unblown cartridge. This advantage is of special importance in making repairs at night or in 50 stormy weather, since, by keeping an extra stock of casing doors and cartridges, the blown fuses may be repaired in the light and under cover at any time, and not necessarily where the fuse is located and under adverse 55 conditions.
- Figs. 6 and 7 show a fuse adapted for mounting openly. The cartridge is like that previously described, comprising the outer tube 1 within which is telescopically arranged the inner tube and a fuse link. The upper and lower terminals 2 and 3 are provided with the switch blades 6 and respectively with the fuse-link clamping nuts 21 and 28. The collar 11 carries a stop 16 but in this construction does not carry the bearing 60 trunnions. Immediately below terminal 3 is a split collar 36 clamped to tube 1 by screws 37. Collar 36 has a pair of downwardly extending arms 38, the lower ends of which are formed into trunnions 39. Trunnions 39 rest in open topped bearings formed in a pair of arms 40 which depend from an insulator 41. Insulator 41 is adapted to be mounted in position in any of the usual ways. Insulator 41 also carries the switch 65 clip 7 with which the lower switch blade 6 cooperates. The upper switch clip 7 is carried by an insulator 42. The cartridge may be readily turned upon its trunnions 39 to open and close the circuit, by a handle 43 which projects from upper terminal 2. The open position is limited by a pair of inwardly projecting lugs 43 carried by arms 40 and against which the under side of arms 38 70 abut. The operation of the cartridge of this fuse is the same as that previously described. The vent for the pressure chamber opening at a considerable distance from the terminals prevents the gases from forming a path for 75 an arc between the terminals outside of the tubes.
- Figs. 8 to 12 inclusive show a modified construction wherein the cartridge is enclosed in a porcelain or other insulating body. The outer casing 45 comprises a hollow body whose bore is enlarged at the top and bottom. The upper enlargement is provided, adjacent its bottom, with threads 46 which may be molded with the body. These threads receive a hollow nut 47, which may be 80 of lead or other suitable material, for clamping one end of the fuse-link as will be herein-after described.
- The cartridge comprises an outer tube 48 of fiber or other insulating material. Tube 48 is open at both ends. Its lower end is threaded to receive the corresponding threads on the inner wall of a recess in a handle plug 49. Plug 49 supports the fuse 85 cartridge. A substantially Z-shaped switch blade 50 has one end resting against the bottom of the plug recess and its other end overlies the upper end of the plug where it is in a position to be inserted between the jaws of and clamped by a switch clip 51. Blade 50 which forms one fuse terminal is secured to plug 49 by a screw 52. Clip 51 is secured to the under side of the lower 90 enlargement in tube 45 by a pair of screws 53 and to it one line conductor is clamped. The other fuse terminal comprises a sleeve 95 54 secured to tube 48 by a screw 55. A split metal sleeve 56 having an outwardly projecting flange 57 is adapted to fit over sleeve 54. The other line conductor is coiled about sleeve 56 and is clamped in place between the flange 57 and nut 47. Nut 47 may be provided with openings 58 for the insertion of a suitable tool to facilitate its 100 rotation. An insulating washer 59, having 105
- 110
- 115
- 120
- 125
- 130

a press fit within the bore of body 45, but a comparatively loose fit with tube 48 so that the tube may be moved therethrough, is forced into the bore between its upper 5 end and nut 47.

Telescopically arranged within tube 48 is a slidable inner tube 60 which is open at its lower end but closed at its upper end by a plug and cushion 61. The two tubes 48 10 and 60 are provided with small openings 62 in their side walls through which one end of a fuse-link 63 may pass when the openings are in alignment. This end of the link is secured to collar 54 by a screw 64. 15 The inner tube also has a vent opening 65. The other end of the link passes through a metal plug 66, which closes the lower end of tube 48, and is clamped in place between plug 66 and switch blade 50 when tube 48 20 is screwed home within the recess in plug 49.

A metal hood 67 covers the upper end of the fuse, being secured to the porcelain body 45 by inwardly projecting ribs 68. Between 25 the ribs the hood is spaced from the body to allow ready escape of the gases.

The action of the gas pressure upon the telescopically slidable tubes 48 and 60 when excess current passes through the fuse-link 30 is precisely the same as that previously described. The path inside the tubes between the terminals is effectively severed and blocked when the alignment of the openings is broken, and the gas chamber is 35 vented. The formation of an arc between the end of the ruptured link or the lower terminal and the upper terminal through the vent opening is prevented by the insulating washer 59. The entire cartridge may 40 be removed for inspection and replacement of the link by turning plug 49 until switch blade 50 is disengaged from clip 51 and then pulling the cartridge out of the bore of body 45.

45 Figs. 13 to 15 inclusive show a modified construction particularly adapted for use with the ordinary spring fuse clips.

The cartridge comprises a fiber outer tube 50 and a telescopically slidable inner fiber tube 71. These tubes are provided with openings 72 through which a fuse link 73 passes when the openings are in alignment. The inner tube is open at one end and closed at the other.

55 One end of the outer tube is threaded to receive the threaded end of a metal ferrule 75. Ferrule 75 forms one terminal of the fuse cartridge. This end of the outer tube is closed by a metal disc 76. Disc 76 has a 60 small opening 77 for the passage of the fuse link, which is clamped between the outer surface of the disc and a screw cap 78. The opposite end of the tube is open, and carries a metal ferrule 79. Ferrule 79 is secured to tube 70 by having one edge

spun into the fiber, or by any other suitable means, and is externally threaded throughout a portion of its length to receive a threaded metal terminal cap 80. One end of the fuse-link is fastened beyond the 70 aligned openings in the tubes by being clamped between the edge of cap 80 and a shoulder 81 on ferrule 79. Cap 80 is vented by an opening 82. This fuse is readily inserted in spring terminal clips 83 which 75 embrace the metal terminal ferrule 75 and cap 80. This fuse also operates in the manner hereinbefore described, except that the chamber is not vented by an additional opening in the inner tube. Whatever gases 80 escape between the tubes can pass out of cap 80 through opening 82.

While the telescopically arranged tubes are shown as having a circular cross section they may assume other forms, such as 85 square, rectangular, etc. The types of fuse shown are merely for the purpose of illustrating a few of the embodiments of the invention, since other forms will readily occur to those skilled in the art. 90

What I claim is:

1. A fuse comprising a pair of spaced terminals, a pair of telescopic tubular members closed at opposite ends thereof to form a chamber, and a fuse link between the terminals, said fuse link being fastened at one end to one tube and extending into the other tube and producing in the chamber a gas pressure upon the volatilization of the fuse link due to excess current therethrough to cause relative movement of the tubular members so as to interrupt any circuit between the terminals. 95

2. A fuse comprising a pair of telescopically relatively slidable tubes closed at 105 their opposite ends to provide a chamber, a pair of spaced terminals, and a fuse link extending into the chamber between said terminals, said fuse link being fastened to the outer tube and extending into the inner tube, the gas pressure produced by the volatilization of said link causing said tubes to move relatively to each other to interrupt any circuit between said terminals. 110

3. A fuse comprising an outer tube having one end closed, an inner tube having a closed end and telescopically arranged within and closing the open end of the outer tube, a pair of spaced terminals, and a fuse link extending between said terminals longitudinally within said tubes and through aligned openings therein, the gas pressure produced by the volatilization of said link upon the passage of excess current therethrough causing relative movement of said tubes to interrupt the circuit between said terminals by the breaking of the alignment of the openings. 115

4. A fuse comprising a pair of telescopically slidable tubes forming a gas chamber, 120

- a pair of terminals, and a fuse-link within said chamber to complete a circuit between said terminals, the pressure of gas within the chamber produced by the volatilization 5 of said link causing relative movement between said tubes to first interrupt any circuit between said terminals and subsequently to relieve the pressure of gas within the chamber.
- 10 5. A fuse comprising a pair of telescopically relatively slidable tubes closed at separated points to provide a chamber, a pair of spaced terminals, a fuse-link extending into the chamber between said terminals and producing a gas pressure upon volatilization 15 of the fuse-link due to excess current therethrough to cause relative movement between said tubes to interrupt the circuit between said terminals, and means for venting said 20 chamber to allow the escape of the gas therefrom after the circuit is interrupted.
6. A fuse comprising a pair of telescopically arranged tubes having their opposite ends closed and provided with aligned openings through their side walls, a pair of spaced terminals for the outside tube, and a fuse-link extending within said tubes and through the aligned openings, to complete a 25 circuit between said terminals.
- 30 7. A fuse comprising a pair of telescopically arranged tubes having their opposite ends closed to form a chamber and provided with aligned openings through their side walls, a pair of spaced terminals mounted 35 on the outside tube, and a fuse link extending between said terminals through the chamber and the aligned openings.
8. A fuse comprising a pair of telescopically arranged tubes forming a chamber 40 and adapted to slide relatively to each other, said tubes being provided with aligned openings, a pair of spaced terminals, and a fuse-link extending into the chamber through said aligned openings to complete a circuit 45 between said terminals, the blowing of said link causing the positive interruption of any circuit between said terminals by providing relative movement between said tubes to break the alignment of the openings.
- 50 9. A fuse comprising a pair of telescopically arranged tubes having their opposite ends closed to form a chamber and provided with aligned openings, the inner tube also having a vent opening, a pair of terminals 55 mounted on the outside tube, and a fuse-link extending between said terminals through the chamber and the aligned openings and acting to hold the tubes in such a position that the vent opening is closed by the outside tube when the link is intact, the gases produced by the volatilization of said link 60 acting to cause relative movement between said tubes so that the aligned openings are separated and the vent opening is beyond the open end of the outer tube.
10. A fuse comprising an outer tube closed at one end and having an opening through the side wall thereof, a pair of spaced terminals therefor, an inner tube closed at one end and slidably within the outer tube and having 70 an opening aligning with the opening in the outer tube, and a fuse-link extending between said terminals and through said aligned openings.
11. A fuse comprising an outer tube 75 closed at one end and having an opening through its side wall, a pair of spaced terminals mounted upon the outside of said outer tube, an inner tube closed at one end and slidably within the outer tube and having 80 an opening aligning with the opening in the outer tube, and a fuse-link extending within said tubes between said terminals and through the aligned openings.
12. A fuse comprising an outer tube of 85 insulating material closed at one end and having an opening through the side wall thereof, a pair of spaced terminals mounted upon the outside of said outer tube, an inner tube closed at one end and slidably within 90 said outer tube and having a pair of openings one opening aligning with the opening in the side wall of the outer tube and the other opening being closed by the wall of the outer tube before the fuse is blown, and a 95 fuse-link extending between said terminals within said tubes and through the aligned openings therein to complete the circuit between said terminals and normally support the inner tube.
13. A fuse comprising a pair of telescopically arranged tubes, a chamber formed within said tubes, and a fuse-link within 100 said chamber extending through aligned openings in the walls of said tubes, the gas 105 pressure produced by volatilization of said link upon the passage of excess current therethrough causing relative movement of said tubes to interpose a non-conducting wall across the path of said link.
14. A fuse comprising a pair of telescopically arranged tubes, each of which is open at one end, a chamber formed within said tubes, and a fuse-link in said chamber, the 110 gas pressure produced by volatilization of said link upon the passage of excess current therethrough causing relative movement of said tubes to interpose a non-conducting wall across the path of said link.
15. A fuse comprising a pair of telescopically arranged tubes and a fuse-link therein, the gas pressure produced by volatilization of the fuse-link causing relative movement between said tubes to positively interrupt the circuit and provide an indication 115 that the fuse is blown.
16. A fuse comprising a fuse-link and a pair of telescopically arranged members forming a chamber within which said link is located, the gas pressure produced in the 120 125 130

chambers upon the volatilization of said link causing relative movement between said members to give an indication that the fuse is blown.

5 17. A fuse cartridge comprising a pair of terminals, a pair of telescopically arranged and relatively movable tubes coacting to form a gas chamber, a fuse-link completing a circuit between said terminals and extending 10 into said chamber, said link volatilizing upon the passage of excess current therethrough, producing a gas pressure within the chamber to cause relative movement between said tubes to prevent the formation 15 of an arc between said terminals and vent the chamber.

18. A fuse cartridge comprising a pair of telescopically arranged tubes forming a gas chamber and provided with aligned openings 20 through their side walls, and a fuse-link anchored at both ends and extending into said chamber through the aligned openings, said link upon the passage of excess current therethrough creating a gas pressure within 25 said chamber due to volatilization of said link whereby said tubes are moved relatively to each other to break the alignment of the openings to interrupt the circuit and prevent the formation or maintenance of an arc.

30 19. A fuse comprising an outer tube having one end closed, an inner tube telescopically arranged within the outer tube, a pair of spaced terminals, and a fuse link extending 35 between said terminals longitudinally within said tubes and through aligned openings therein, the gas pressure produced by the volatilization of said link upon the passage of excess current therethrough causing relative movement of said tubes to interrupt 40 the circuit between said terminals by breaking the alignment of the openings.

20. A fuse comprising an outer tube closed at one end and having an opening 45 through the side wall thereof, a pair of spaced terminals therefor, an inner tube slidably within the outer tube and having an opening alining with the opening in the outer tube, and a fuse-link extending between 50 said terminals and through said aligned openings.

21. A fuse comprising an outer tube closed at one end and having an opening through its side wall, a pair of spaced terminals mounted upon the outside of said outer tube, an inner tube slidably within 55 the outer tube and having an opening alining with the opening in the outer tube, and a fuse-link extending within said tubes between said terminals and through the aligned openings.

60 22. A fuse comprising an outer tube of insulating material closed at one end and

having an opening through the side wall thereof, a pair of spaced terminals mounted upon the outside of said outer tube, an inner tube slidably within said outer tube and having a pair of openings, one opening alining with the opening in the side wall of the outer tube and the other opening being closed by the wall of the outer tube before 70 the fuse is blown, and a fuse-link extending between said terminals within said tubes and through the aligned openings therein to complete the circuit between said terminals and normally support the inner tube. 75

23. A fuse comprising a pair of telescopically slidable tubes, a pair of spaced terminals mounted on the outside of the outer tube, a fuse-link passing through the inner tube and having its outer end secured to the terminals, the pressure of gas within the inner tube produced by the volatilization of said link causing the outer end portion of the inner tube to move out of the outer tube and positively interrupt the circuit. 80

24. An expulsion fuse comprising a plurality of relatively movable tubular telescoping receptacles, the outermost of which is substantially closed at one end and having its other end open to the atmosphere and a fusible element for releasably holding the receptacles in telescoped position and adapted to release the interior receptacle when the fuse is ruptured. 90

25. In combination, in an expulsion fuse, 95 a pair of separate terminal members, a fusible element for connecting the members and a casing for enclosing the fusible element adapted to be elongated by the arc gases incident to rupture of the fusible element for increasing the length of the path of the arc between the terminals. 100

26. In combination, in an expulsion fuse, 105 a pair of separate terminal members, a fusible element for connecting the members, a casing for enclosing the fusible element and means movable longitudinally of the casing and actuated by arc gases incident to the rupture of the fusible element for increasing 110 the length of the path of the arc between the said terminals.

27. The combination with a pair of separate fixed terminal members, a tubular casing and a fusible element for connecting the terminal members disposed longitudinally of the casing, of a means actuated by gases of volatilization of the fusible member and movable longitudinally of the casing for increasing the length of the path of the arc between the terminal members. 115 120

In witness whereof, I have hereunto subscribed my name.

JOHN P. ARNDT.
